SEWING MACHINE

Sidney R. Bell, Stamford, Conn., assignor to
Irving J. Moritt, Brooklyn, N. Y.

Application July 17, 1952, Serial No. 299,391

3 Claims. (Cl. 112—237)

This invention relates to swing machines, and more particularly to a miniature, light-weight, electrically driven sewing machine.

The primary object of my invention is to generally improve sewing machines, especially small, light-weight sewing machines intended to be readily portable.

Other objects center about the presser foot, and one feature is the provision of adjustment of the position of the presser foot, and also of the spring tension exerted thereon.

Many features of the present sewing machine are not claimed herein but are claimed in my copending application Serial No. 85,191, filed April 2, 1949, or in divisional or continuation-in-part applications thereof. Division of said parent application Serial No. 85,191 was required, and the present application is a continuation-in-part of one of the divided portions of said parent application.

To accomplish the foregoing general objects, and other more specific objects which will hereinafter appear, my invention resides in the sewing machine elements and their relation one to another as are hereinafter more particularly described in the following specification. The specification is accompanied by drawings in which:

Fig. 1 is a side elevation of a sewing machine embodying features of my invention;

Fig. 2 is a transverse section taken approximately in the plane of the line 2—2 of Fig. 1;

Fig. 3 is a fragmentary elevation taken at the end of the sewing machine arm looking in a direction opposite to that of Fig. 1;

Fig. 4 is a view similar to the upper part of Fig. 3, but showing a modified form of the invention;

Fig. 5 is a fragmentary view generally similar to Fig. 4 but showing the lifting cam in down or released position to make the work feed operative; and

Fig. 6 is a fragmentary horizontal section taken approximately in the plane of the line 6—6 of Fig. 5.

Referring to the drawing, the sewing machine is shown in Fig. 1, it comprising an arm 12 overhanging a bed 14. The bed houses work feed and shuttle mechanism covered by a removable plate 16. The stitch length may be controlled by an adjustment indicated at 18. The direction of work feed may be reversed by a control indicated at 20. A bobbin from the shuttle may be rewound with thread from spool 24 by means of a shaft end projecting at 26. The machine is electrically driven, connection being made at 28 by means of a suitable plug, not shown, the connection preferably including a suitable speed control rheostat, not shown, arranged to be operated by either the knee or the foot, as shown in my Patent No. 2,561,556, granted July 24, 1951.

The sewing machine head is preferably arranged to be carried in a small carrying case, not shown in the present drawings, but illustrated and described in my copending application Serial No. 40,917, filed July 27, 1948. The sewing machine is readily portable and very tiny in di-

2

mension. To increase the work table area and to steady the machine, as described in said copending application, it is received in a mating opening in the case, which opening closely surrounds and comes flush with the top of the bed 14. To facilitate release of the then-surrounded needle plate 16, a pushbutton 32 is provided.

For the most part the sewing machine details are not described herein, being described in my aforesaid copending application Serial No. 85,191. The description 10 there includes the main drive, and the work feed mechanism. As to the latter, it may be sufficient for the present purposes to point out that it comprises a vertical feed plate disposed in the bed 14 of the machine, and that it has a serrated upper edge shown at 92 in Fig. 2. This plate is slidably held by appropriate guide walls in the bed of the machine, which serve to hold the plate in erect position while affording the horizontal and vertical movement.

The description in my copending application Serial No. 20 85,191 also details the stitch length control mechanism centering about the adjustment 18; the reverse feed mechanism centering about the control knob 20, the shuttle, shuttle carrier, and drive mechanism, and the relation between the shuttle and the needle 80, which needle is secured to a vertically reciprocable needle bar 66 by means of a thumbscrew 82. It also details the thread tension mechanism centering about the parts 224 and 230; the bobbin wind mechanism utilizing the upper end of the motor shaft shown at 26; and the lamp and other 30 miscellaneous details of the sewing machine.

Referring to Figs. 2 and 3 of the drawing, a presser foot 190 cooperates with the serrated edge of the feed plate. The presser foot 190 is pivoted on a bracket 194 detachably secured to rod 196 by means of a thumbscrew 198. The rod 196 is held against rotation by means of a pin 200 slidably in slots 202. The rod 196 is urged downwardly by a compression spring 204, the tension of which may be adjusted by means of a threaded bushing 206. This is knurled at 208 to facilitate rotation and 40 adjustment of the spring pressure.

The pin 200 is prolonged for cooperation with a control handle 210. The handle is pivoted at 212 and may be swung to any of three positions. The position shown in Figs. 2 and 3 is the normal sewing position, in which 45 the presser foot may descend to lowermost position, and in the absence of fabric bears directly against the feed plate. This is shown in Fig. 3 by the flat 214 located at the lower end of slot 202 and well below the position of pin 200.

50 However, by turning the handle 210 from the solid line position to the broken line position 210', the flat 216 is brought into operation, and this raises the pin 200 slightly, thus providing a small space between the presser foot and the feed plate, suitable for darning. By swinging the handle 210 in the opposite direction to the position 210', the flat 218 is brought into operation, thereby raising the pin 200 to the elevated position 200', which releases the work entirely.

A modified form of the presser foot mechanism is 60 shown in Figs. 4, 5 and 6 of the drawing. It is improved in several respects. One is that the angle of the presser foot may be adjusted slightly to one side or the other, in order to best locate the presser foot aperture 350 (Fig. 6) in respect to the needle 80 (Figs. 1 and 2). Another is the provision of a hardened steel wear plate 362 to guide the cam follower pin 300. This is preferable to slots formed directly in the cast head as shown in Figs. 2 and 3, for the cast metal is preferably a light metal such as aluminum, which may tend to wear and thus permit slight changes in the orientation of the presser foot about the axis of the bar 196 carrying the same.

Considering the modified arrangement in greater detail, and referring first to Fig. 5, the slot 364 cut through the cast head 312 is made oversized in width, in order to have no controlling influence on the position of the pin 300, and consequently the rod 296 and the presser foot 290. The slot 302 in the wear plate 362 is made to just fit the pin 300. The plate may be made of hardened steel, and is secured to a somewhat raised flat surface 366 on the side of the cast head 312.

The plate is secured in position by an upper screw 368 and a lower screw 370. The holes through the plate are slots extending in horizontal direction, so that the plate may be shifted slightly to one side or the other by first loosening the screws 368 and 370. It is evident that this will slightly rotate the rod 296 and thus shift the orientation of the presser foot 290. This moves the location of the needle hole (350 in Fig. 6) to the left or right when viewed as in Fig. 1, until it is appropriately aligned with the position of the needle 80.

The upper screw 368 (Figs. 4 and 5) acts as a simple screw bearing directly against the steel wear plate. However, the lower screw 370 acts also as a bearing for the lift lever 310. For this purpose the screw 370 is a stepped or shouldered screw, as is best shown in Fig. 6, so that when tightened the shoulder thereon will bear against and lock the steel wear plate against movement, without however binding the lift lever against movement, the latter turning freely on the intermediate stepped or shouldered portion of the screw 270.

The modified lift lever is generally like that shown in Fig. 3 in having three main cam parts. The part 314 is at minimum radius and permits the presser foot in rest directly on the serrations 92 of the feed dog. The part 316 is at intermediate radius and raises the feed dog slightly. The lever 310 is turned in clockwise direction to use the part 316. The part 318 is at maximum radius and fully raises the presser foot. The lift lever is turned in counter-clockwise direction to make use of the part 318, as shown in Fig. 4.

The lever is an angle lever provided with an extra handle 372. This is convenient when changing the presser foot from raised to lowered position to begin sewing, for in raised position the main handle 310 is upright and located behind the machine, when viewed as in Fig. 1, but the extra handle 372 projects horizontally, as shown in Fig. 4, and is easily pushed downward, following which the lever falls the rest of the way to the position shown in Fig. 5.

Moreover, in the position of Fig. 4 the arm 372 is so weighted as to keep the angle lever at an angle such that the arm 310 is disposed out of the way of standard attachments such as a buttonholer or a zig-zag attachment. In practice the part 310 is somewhat more to the right than is shown in Fig. 5.

It is believed that the construction, operation, and method of use, as well as the advantages of my improved presser foot arrangement, will be apparent from the foregoing detailed description. It will also be apparent that while I have shown and described the invention in several forms, changes may be made in the structures disclosed without departing from the scope of the invention, as sought to be defined in the following claims.

I claim:

1. In a sewing machine, a sewing machine arm, a needle bar and needle, a presser foot having a part located adjacent the path of said needle, a round rod borne in said arm and carrying the presser foot, resilient means urging the presser foot downwardly, a pin projecting side-

wardly from the rod, said arm having an opening to receive said pin, said foot and rod and pin all being in fixed relative orientation, a wear plate secured outside the arm and provided with a vertical slot dimensioned to slidably receive the pin to prevent rotation of the rod and presser foot, and releasable screws securing said plate to said arm, said plate having horizontal slots receiving said screws to afford sideward adjustment of the plate and consequent adjustment of the orientation of the presser foot relative to the needle, and said opening in said arm being wider than said slot in said plate in order to accommodate said sideward adjustment.

2. In a sewing machine, a sewing machine arm, a needle bar and needle, a presser foot having a part located adjacent the path of said needle, a round rod borne in said arm and carrying the presser foot, resilient means urging the presser foot downwardly, a pin projecting sidewardly from the rod, said arm having an opening to receive said pin, said foot and rod and pin all being in fixed relative orientation, a wear plate secured outside the arm and provided with a vertical slot dimensioned to slidably receive the pin to prevent rotation of the rod and presser foot, one end of said pin being prolonged beyond the slot to act as a cam follower, a rotatable cam mounted on said sewing machine and bearing against said pin to raise or lower the presser foot, a finger piece for turning the cam, and releasable screws securing said plate to said arm, said plate having horizontal slots at said screws to afford sideward adjustment of the plate and consequent adjustment of the orientation of the presser foot relative to the needle, and said opening in said arm being wider than said slot in said plate in order to accommodate said sideward adjustment.

3. In a sewing machine, a sewing machine arm, a needle bar and needle, a presser foot having a part located adjacent the path of said needle, a round rod borne in said arm and carrying the presser foot, resilient means urging the presser foot downwardly, a pin projecting sidewardly from the rod, said arm having an opening to receive said pin, said foot and rod and pin all being in fixed relative orientation, a wear plate secured outside the arm and provided with a vertical slot dimensioned to slidably receive the pin to prevent rotation of the rod and presser foot, one end of said pin being prolonged beyond the slot to act as a cam follower, a rotatable cam bearing against said pin to raise or lower the presser foot, a finger piece for turning the cam, and releasable screws securing said plate to said arm, said plate having horizontal slots at said screws to afford sideward adjustment of the plate and consequent adjustment of the orientation of the presser foot relative to the needle, and said opening in said arm being wider than said slot in said plate in order to accommodate said sideward adjustment, one of said screws acting also as a pivot for said cam and finger piece, said latter screw being shouldered so that it may be tightened against the plate without locking the cam and finger piece against free rotation.
